UNITED STATES PATENT OFFICE.

LOUIS TILLIERS, OF NEW YORK, N. Y.

MOTIVE POWER.

Specification of Letters Patent No. 33,112, dated August 20, 1861.

To all whom it may concern:

Be it known that I, LOUIS TILLIERS, of New York, in the county and State of New York, have invented a new and Improved 5 Motive Power; and I do declare the following to be a full, clear, and correct description thereof, reference being had to the accompanying drawings, in which like parts of the invention are indicated by the same 10 letters of reference, and which drawings will be alluded to hereinafter.

The nature of my invention consists in the construction and operation of a motive power as herein set forth.

15 To enable those skilled in the arts to make and use my invention I will speak of its construction and operation.

Construction.—L shows a series of uprights composing the frame-work for supporting the operative parts of my improved 20 motive power.

s s show a shaft of peculiar construction, to which two (2) sets of levers A and B are attached, so as to revolve with the same.

25 The levers marked A are shorter than those marked B and are provided with the stopping points o and d.

The levers B are provided with weights W of any undetermined quantity, and have 30 attached to one end the catches h and n, intended to operate in connection with the stopping points o and d.

T shows stationary racks placed upon the uprights L, above and below the shaft s s 35 and into which the cog-wheels R attached to and moving with the levers B gear, for the purpose of assisting in lifting the weights W.

m and m' are projections of an inclined 40 shape, the former (m) attached to the uprights L; the latter (m') to the supports G, for the purpose of throwing forward and operating the stops o and d, which are provided with springs for this purpose.

g shows bars attached at the necessary 45 distance from the top of the uprights L to stop and retain in position the levers B, that the cog-wheels R may gear into the racks T at the proper time.

g' shows wedge-shaped pieces, placed at 50 the bottom of the apparatus and between the uprights L for the same purpose as g.

Z shows a fly-wheel and H, U, and V a 55 brake for controlling the same.

Operation.—The apparatus having been thus constructed and the levers B having been placed in the position shown in Figure 1,

it will be seen that six (6) of the weights W, have a tendency to fall. The two remaining weights, at the opposite end of the shaft, s, s, from the fly wheel Z, are to be raised. As 60 the six (6) weights W fall, they impart motion to the shaft s, s, causing the same to revolve. As the shaft s, s, revolves the levers A are carried with it. The ends of the levers B being stopped and retained in position, the cog-wheels R gear into the racks T at the proper moment and the weights (previously alluded to as placed at the end of the shaft s, s opposite the fly-wheel Z) are raised. As the shaft s, s continues to 70 revolve, the stopping points d, d are operated by the inclined catches h, h and the raised weights are prevented from moving beyond the weight L. The stopping points o from the inclined shape of the projections m and 75 m' are thrown forward and the catches n, n, being stopped and held by the same, the levers B, with the levers A revolve with the shaft s, s. As this set of levers B in connection with the two sets nearest the fly 80 wheel Z, fall, the second set of levers is raised, the same operation being repeated as described of the first set and this operation is true of the other sets or any number of sets that may be employed. 85

It is to be remarked that as the racks T represent in degrees the one eighth of the revolution made by the levers B and as the semi-periphery of the cog-wheels R is one third larger than the racks T, I employ the 90 bars g and wedge-shaped pieces g' for the purpose of operating the levers B and holding the same until the difference between the racks and cog-wheels has been traversed by the latter, that the same may gear into the 95 racks at the proper time.

My improved motive-power rests upon a principle, which is, the combination of the lever with that of gravitation. Every one knows how great the power contained in a 100 lever is, and what gravity bodies acquire in falling. I combine these two forces so as to produce a permanent active force, capable of great utility in its application as a motor to the various machines invented by 105 industry.

Fig. 1 is a front view of my motive power and Fig. 2 an end view of the same. In the other drawings various views are shown which will be explained in the 110 following remarks.

In Figs. 3 and 4, a lever A is shown, hav-

ing at each of its arms a movable lever B. The apparatus is made up of four (4) of these levers A and I call these four levers united on the same shaft a system. I may employ two, three or four systems.

The combination of a system is shown in Fig. 7, where the second lever is placed so as to form with the first lever an arc of 45° ; the third with the second and the fourth with the third form similar arcs. Thus the circle described by a lever in revolving is divided into eight equal parts of 45° each. The racks T into which the cog-wheels R gear have a length of 45° ; whence it follows that when two wheels pass over the racks the other six are free and when one wheel has accomplished its revolution the other begins to gear.

It is known (Figs. 5 and 6) that the levers B turn at the same time with their cog-wheels; consequently, the cog-wheels of the first and fourth levers will revolve the dotted levers B and B' Fig. 7. The weight E that was at the point E'' before the wheel of the dotted lever B' geared into the rack T, will place itself at E' ; and the weight D which was at D'' before the cog-wheel of the lever B geared into the rack T' will place itself at D' . As the other cog-wheels gear into the racks T and T' the levers to which these wheels are attached, will accomplish successively the same change of position, a change that will continually place their weights as seen in the first, second, third and fourth levers of the left hand.

But on the other hand, when the cog-wheel of the fourth lever begins to gear into its corresponding rack this lever will be in the position indicated by the line $l\ l$ and the weight D'' of this lever will be at the point y and being raised there, will become null and void, and will only exercise its action again when it reaches the point y' . On the other hand, when the cog-wheel of the first lever begins to gear into its corresponding rack, this lever will occupy the position indicated by the dotted line V , and the weight of this lever at E'' will be at the point y''' and being there raised, the same will become null until it arrives at the point y'' when it begins to act again. Hence it results, that the weights E' and D'' will act as a resisting force, each, during the time their wheels may occupy in passing over the racks T, and that they will operate as a power, only during the passage indicated by the dotted arc from y'' to y .

Having thus described my invention, what I claim as new and desire to secure by Letters Patent is,

The use or employment of the levers A, weighted levers B, shaft s s, in combination with the connections herein described, when the same shall be arranged and operated as described and for the purpose specified.

LOUIS TILLIERS.

In presence of—

A. SIDNEY DOANE,
J. FAEPFEL.
